UNITED STATES PATENT OFFICE.

WINSLOW GOODWIN, OF CHICAGO, ILLINOIS, ASSIGNOR TO CROWE NAME PLATE & MANUFACTURING CO., OF CHICAGO, ILLINOIS, A CORPORATION OF ILLINOIS.

ETCHED METAL BODY.

Application filed April 25, 1925. Serial No. 25,889.

To all whom it may concern:

Be it known that I, WINSLOW GOODWIN, a citizen of the United States, residing at Chicago, in the county of Cook and State of Illinois, have invented new and useful Improvements in Etched Metal Bodies, of which the following is a specification.

My invention relates to etched metal bodies and more particularly to plates, forming the front walls of the cases in which the mechanism of radio apparatus is enclosed.

My primary objects are (1) to provide a body of the character stated and more particularly of plate form, with its exposed surfaces of such character that scratches occurring thereon, either in the manufacture or handling of the body or occurring in use, or other kinds of marks made by handling the body, or imperfections in the metal itself, will not be readily visible; and (2) to provide for the enhancing of the appearance of the body particularly when in plate form and provided to form the front wall of a radio case.

Referring to the accompanying drawings:

Figure 1 is a face view of a plate provided to form the front plate of a radio case and embodying my invention, the ornamentation of the background being shown purely diagrammatically, and Figures 2, 3, 4 and 5, similar, fragmentary, views of the front surfaces of corner portions of the plate, showing in detail a variety of background surfaces.

In illustrating my invention, I have chosen to show it in a plate forming the front wall of a case for radio apparatus involving a plurality of selectors the pointers of which cooperate with dials on the plate, and a rheostat control having a pointer, but without, however, intending to limit the invention to a plate for an apparatus of the particular character referred to.

The plate shown, which is of metal, is produced by the etching process, the dials represented at 7 and 8, together with their designating legends, the curved arrow 6 for indicating the direction for operating the rheostat-controlling member, together with its designating legend, and the various border lines shown, being in relief, with the metal of the plate visible at the face of these relief portions.

The background of the plate shown purely

diagrammatically in Fig. 1 by the stippling, may present any of many forms, as for example as shown in Figures 2, 3, 4 and 5, wherein the inked portions of the background of the drawing represent the visible metal of the plate, namely, the surfaces in relief, and the uninked portions of the background represent the relief-outlining, depressed, surfaces of the plate.

In accordance with the showing in Fig. 2 the background is etched to present a lace-like appearance; in Fig. 3 the background is etched to present an appearance resembling marble; in Fig. 4 the background is etched to present a mottled appearance resembling leather; and in Fig. 5 it is etched to present a more conventional design of general lace-like appearance.

In all of the forms illustrated, and which are shown purely by way of example, the background of the plate is etched to form portions in relief and relief-outlining, or depressed, portions, the latter being represented by the uninked portions of the background on the drawings, whereby the background instead of presenting a smooth etched surface, presents a broken, relatively rough, etched surface, which not only causes the plate to present a highly ornamental effect, adding greatly to the ornamental appearance of the plate, but renders practically invisible, handling marks and scratches on, or imperfections in, the metal of the plate, the provision of the background as stated, being of especial advantage, particularly as regards handling marks and imperfections in the metal, where the depressed portions, presenting etched surfaces of the background, are oxidized or electro-plated, inasmuch as so treating etched surfaces causes them to have marked affinity for oil or grease which is very difficult to remove and which marks are rendered practically undetectable by reason of the provision of the relatively rough background as stated, and imperfections in the metal at its surface are also rendered practically undetectable.

If desired, the etched, depressed portions of the background may be coated with enamel or other desirable coating, preferably opaque and of any desirable color, more particularly a color contrasting with the color of the metal of the plate, whereby the background instead of presenting a uniform, uninterrupted surface color, whether of the

metal of the plate or otherwise, presents a rather finely broken, interrupted surface coloring effect, such interrupted or broken surface coloring effect also being provided 5 by oxidizing or electro-plating the depressed portions of the background, with the advantage of producing a highly ornamental effect which is enhanced by the contrasting effects produced between the dial, or other 10 markings on the plate for cooperation with operative parts of the apparatus, and the background of the plate.

Furthermore, if desired, certain, or all, 15 of the portions in relief of the plate may be covered by a coating material applied thereto, or be electroplated or oxidized, even to such surface extent, if desired, that the entire surface of the plate is so treated, with certain of the advantages above 20 enumerated.

While I have illustrated and described certain particular embodiments of my invention, I do not wish to be understood as intending to limit it thereto as the invention 25 may be embodied in various other forms and presenting other background effects, without departing from the spirit of my invention.

What I claim as new, and desire to secure 30 by Letters Patent, is:

1. An etched metal body having etched portions with an etched background composing a major portion of the surface, said background being broken up into comparatively minute areas comprising portions in 35

relief and portions forming outlining surfaces for said relief portions, whereby visibility of accidental marrings or inherent imperfections is minimized.

2. An etched metal body having etched 40 portions in relief, with an etched background composing a major portion of the surface, said background being broken up into comparatively minute areas comprising portions in relief and portions forming 45 outlining surfaces for said relief portions, whereby visibility of accidental marrings or inherent imperfections is minimized.

3. An etched metal body having etched 50 portions with an etched background composing a major portion of the surface, said background being broken up into comparatively minute areas comprising portions in relief and portions forming outlining surfaces for said relief portions, said outlining 55 surfaces having a covering of a color contrasting with said relief portions, whereby visibility of accidental marrings or inherent imperfections is minimized.

4. An etched metal body having etched 60 portions with an etched background composing a major portion of the surface, said background being broken up into comparatively minute areas comprising portions in relief and portions forming outlining surfaces for said relief portions to cause said 65 background to present a lacelike appearance whereby visibility of accidental marrings or inherent imperfections is minimized.

WINSLOW GOODWIN.
